UNITED STATES PATENT OFFICE.

WILLIAM WATTIE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

STRAW MATTING.

SPECIFICATION forming part of Letters Patent No. 693,090, dated February 11, 1902.

Application filed January 19, 1901. Serial No. 43,939. (No model.)

To all whom it may concern:

Be it known that I, WILLIAM WATTIE, a citizen of the United States, residing at Worcester, in the county of Worcester and State of Massachusetts, have invented certain new and useful Improvements in Straw Matting, of which the following is a specification.

The invention to be hereinafter described relates to straw matting, and more particularly to improvements in the selvage edges of such matting, whereby the production of a uniform and even thickness of matting without liability of unraveling is produced.

Heretofore in the ordinary method of weaving straw matting to form the selvage edges, the filling-straws, which are inserted separately and alternately from opposite sides of the loom, have had turned-in ends which are of reduced size and extend over and beyond the selvage-cord, turned over said cord, and brought to the upper surface of the matting, where they are bound or held in place by the next succeeding pick of straw on the beating up of the lay. The projecting turned-in ends upon the upper surface of the matting have been trimmed off; but this leaves the finished matting in an unsatisfactory condition upon the upper surface last trimmed, and the ends will project somewhat and affect the appearance, as well as the wear, of the matting at its edges. It has been customary to some extent in order to overcome the objection of trimming the projecting turned-in ends of the straws on the face of the matting to turn the said ends back under the warp-threads, inter-weaving said turned-in ends with the warp threads or cords of the matting between the selvages, and then to bring the ends upon the lower surface of the fabric. The objection to this is that the series of loops formed by turning the projecting ends back under the usual warp-threads between the selvages produces longitudinal ridges upon the upper surface of the matting inside the selvage edges, thereby increasing materially the thickness of the matting at its edges over the thickness of the body of the matting. This is a serious objection and not only affects the appearance, but presents ridges, which wear rapidly.

The object of my present invention is to overcome both of the objections hereinbefore noted and to provide a straw matting with improved selvage edges wherein the turned-in ends will be upon the lower surface of the matting and at the same time avoid the production of undue thickness at this point.

In weaving straw matting with my improved selvage edges I employ an auxiliary or supplemental thread and the next of the usual warp cords or threads and also extending in the direction of the length of the matting parallel with and inside of the usual selvage cord or thread. The reduced ends of the filling-straws which are to be turned in extend over and under the selvage cord or thread and under the said auxiliary or supplemental cord or thread. In addition to the auxiliary or supplemental thread or cord I also employ what is termed the "turn-over thread," which extends through an eye or opening in the upper end of a needle and is guided in a slot, so that the movement of said needle at the proper time by mechanism to be described will turn in or carry the extended reduced end of the filling-straw down and under the selvage cord or thread and under or against the auxiliary or supplemental thread or cord and will prevent the end from passing to the upper side of the matting, the said turned-in end being thus bound by the supplemental or auxiliary cord or thread and the turn-over thread without being interwoven with the usual warp threads or cords of the fabric. On the next succeeding pick of the filling-straw from the opposite end of the loom on the beating up of the lay the turn-over thread will be bound in to hold the turned-in end extending under the selvage-cord and the supplemental cord or thread, and thus the operation is repeated alternately at each edge of the straw matting to form the selvage edge thereon.

In the drawings I have shown only sufficient of a straw matting with my improved selvage edges to enable those skilled in the art to which my invention belongs to understand the same.

Referring to the drawings, Figure 1 is a plan view of sufficient of a straw matting to

illustrate my invention, some of the straws being shown separated from the remainder of the fabric to illustrate the manner of tying in, to be hereinafter described. Fig. 2 is an edge view of the fabric looking in the direction of the arrow *d*, Fig. 1. Fig. 3 shows the under surface of the matting illustrated in Fig. 1. Fig. 4 is a diagram to show the relative positions of the filling-straws, the longitudinal warp-threads, the selvage cord or thread, the supplemental warp or binder thread, and the turn-over thread, the parts being shown with the shed open and before the operation of the needle to move the turn-over thread to turn in the reduced end of the straw; and Fig. 5 shows the position of the several parts after the operation of the needle to move the turn-over thread in turning in the reduced end of the straw, with the shed closed on the beating up of the lay.

In the drawings, 37 represents the usual warp threads or cords, which run longitudinally of the fabric and which are preferably disposed across the entire width of the fabric at a uniform distance apart, and 40 represents the weft or filling straws, which are woven alternately over and under the regular warp-threads 37 throughout the width of the fabric.

In weaving straw matting the straws usually employed are larger at one end than at the other, and to produce a selvage on either side of the matting these straws are introduced alternately between the warp-threads from opposite sides of the loom, with the larger end leading, as indicated by the arrow *e* in Fig. 4, while the smaller ends of the straws project beyond the selvage warp-thread 37, and in disposing of these smaller ends of the straws on opposite sides of the fabric it has heretofore been proposed to turn said smaller ends back into the fabric and interweave them with the regular warp-threads 37. In the improved construction of fabric which forms the subject of my present invention I have provided between the selvage cord or thread 37 and the next adjacent regular warp-thread of the fabric an auxiliary thread 38, preferably disposed in near proximity and parallel to the selvage cord or thread 37, and between said auxiliary thread and the next adjacent regular warp-thread of the fabric I employ what I will designate a "turn-over thread" 39, and in disposing of the smaller projecting ends of the straws I turn said ends over and around the selvage cord or thread 37, under the auxiliary thread 38, and over the turn-over thread 39, the smaller ends of the straws projecting from this point toward the back of the fabric, from whence they may be removed by cutting off, if desired.

It will be noted from the construction of fabric described that the smaller ends of the straws are not interwoven with the regular warp-threads of the fabric and do not, in fact, rise to the upper surface at all, as would be

the case were they regularly woven with the warp-threads, and it will be also noted that the turned-in and smaller ends lie alongside of and parallel to the straws of which they are a part and on the same side of the auxilliary and turn-over thread as the body portion of their respective straws, the result of which is that on the beat-up of the lay the smaller ends are crowded close up to and to some extent beneath the body portion of their respective straws, thus obviating their appearance upon the surface of the fabric and the production of ridges, which would be subject to rapid wear.

In order that the manner of weaving my improved fabric may be more fully understood, reference is had to Figs. 4 and 5; in which the large end of the straw 40 is fed in the direction of the arrow *e*, under the turn-over thread 39, over the selvage-cord 37, under the supplemental warp-thread 38, and then regularly between the sets of warp-threads 37, the shed during this time being open, as shown in Fig. 4. The small end of the straw 40 is left extending beyond the selvage-cord 37, while the turn-over thread 39 is carried by a needle 13, which is given movement by any suitable form of mechanism, so as to carry said turn-over thread from the position shown in Fig. 4 to that shown in Fig. 5 in the direction of the arrow, Fig. 5, whereby the turn-over thread 39 carries the reduced end of the straw 40 around the selvage-cord 37 and under the auxiliary thread 38, so that it extends from over the turn-over thread 39 and toward the back of the fabric. The parts being in this position, the shed is now closed as the reed has reached the fell of the matting. On the following pick a filling-straw from the opposite side of the lay is inserted and passes under the turn-over thread 39, while it is in the position shown in Fig. 5, and binds the same into the body of the matting on the beating up of the lay. The needle 13, carrying the turn-over thread 39, is then returned to the position shown in Fig. 4, and the succeeding pick leaves a straw with the small end under the turn-over thread 39, as shown in Fig. 4, and the operation of forming the selvage edge is repeated in the sequence above shown and outlined.

It will be understood, of course, that the selvage is formed on each edge of the matting in the manner above described for one edge thereof.

The advantages of a selvage formed by the disposition of parts as noted and by the use of the auxiliary thread 38 will be appreciated by those skilled in the art. The turned-in end of the straw is not carried to the upper surface of the matting, as would be the case if it were interwoven with the regular warp-threads of the matting, but extends to and upon the lower surface thereof, leaving the upper surface smooth and even, and by means of the supplemental or auxiliary thread 38 the turned-in end is bound into the body of the

fabric, at the edge thereof, so that the turned-in end of the filling straw cannot become detached.

Having thus described my invention, what I claim as new, and desire to secure by Letters Patent, is—

1. A straw matting comprising filling-straws and the usual warp cords or threads, an auxiliary or supplemental thread or cord parallel to and between the selvage and next adjacent warp cord or thread, and a turn-in thread parallel to the auxiliary or supplemental thread or cord, the smaller ends of the filling-straws being passed around and under the selvage warp cord or thread and under and over the auxiliary and turn-in threads, respectively.
2. A straw matting comprising filling-straws and the usual warp cords or threads, an auxiliary or supplemental thread or cord parallel to and between the selvage and next adjacent warp cord or thread, and a turn-in thread parallel to the auxiliary or supplemental thread or cord, the smaller ends of the filling-straws being passed around and under the selvage warp cord or thread and under and over the auxiliary and turn-in threads, respectively, the said turned-in end being bound and held in place by the next succeeding pick of straw.
3. A straw matting comprising filling-

straws and the usual warp cords or threads, an auxiliary or supplemental thread or cord between the selvage and next adjacent warp cord or thread, and a turn-in thread parallel to and adjacent the auxiliary or supplemental thread or cord, the smaller ends of the filling-straws being passed around and under the selvage warp cord or thread and under and over the auxiliary and turn-in thread, respectively, the turned-in end of the filling-straw being free from interweaving with the usual warp cords or threads between the selvages.

4. A straw matting comprising filling-straws and the usual warp cords or threads, a fine auxiliary or supplemental thread or cord between the selvage and next adjacent warp cord or thread, and a turn-in thread parallel to and adjacent the auxiliary or supplemental thread or cord, the smaller ends of the filling-straws being passed around and under the selvage warp cord or thread and under and over the auxiliary and turn-in thread, respectively, the turned-in end of the filling-straw being free from interweaving with the usual warp cords or threads between the selvages.

WILLIAM WATTIE.
